UNITED STATES PATENT OFFICE.

ROBERT ROMAINE, OF OTTAWA, ONTARIO, CANADA.

ICE-BREAKING VESSEL.

SPECIFICATION forming part of Letters Patent No. 355,214, dated December 28, 1886.

Application filed June 30, 1886. Serial No. 206,720. (No model.)

To all whom it may concern:

Be it known that I, ROBERT ROMAINE, gentleman, of Ottawa, in the county of Carleton, Dominion of Canada, have invented certain 5 new and useful Improvements in Vessels for Breaking and Removing Ice, of which the following is a specification.

This invention has for its object and purpose, first, the keeping open during winter 10 seasons of navigable waters and streams for the purpose of preventing compacted and field ice accumulating and forming into jams, thereby causing floods and inundations through the breaking up of the ice in running streams, 15 rivers, and lakes; and, second, the breaking and smashing into small pieces and then removing the solid bodies of thick ice in early spring, after having accumulated and fastened during the previous winter season around and 20 between wharves, basins, and harbors, thereby facilitating the early navigation and arrival of vessels in the spring and prolonging their stay in the fall of the year.

To these ends the invention consists in providing the vessel with devices for crushing or 25 breaking the ice and conveying it thence underneath the vessel, and discharging it at the opposite end thereof into the open stream.

In the accompanying drawings, Figure 1 is 30 a front end view of my improved machine; Fig. 2, a longitudinal vertical section, and Fig. 3 a rear end view with the operating mechanism removed.

A indicates the shell of a rectangular-shaped vessel, B, formed of thick iron or steel plates, the plates of course being of gradually-decreasing thickness above the load-line. The front end of this shell inclines rearwardly from the point where it joins the deck C, and its 40 rear end is also inclined; but it will be noticed that the rear inclined wall does not extend out to the rear end of the deck C, but allows the latter to overhang for a considerable distance, as shown in Fig. 2, thus forming a chamber, D. This construction allows a free circulation of water in the chamber D, and in this chamber I mount a pair of twin screws, 45 E, the blades and shaft of which are thoroughly protected from ice or other floating 50 substance.

The interior walls of the shell A will of

course be suitably braced and backed up by a solid wooden frame-work, in order to resist the immense pressure it will at times be subjected to. This class of building is well understood in the construction of vessels for navigating the Arctic seas, and does not require illustration here.

F F F are four strongly-built iron keels, of tubular construction, and filled with elm, 60 oak, or other suitable timbers. These keels extend parallel with and are bolted or riveted to the bottom face of the shell A, and at the bow of the vessel they conform to the front inclined wall of shell A and overhang a slight 65 distance, where they are secured to a heavy rectangular frame-work, G, which latter is adapted to receive the shocks and blows given the vessel. At the rear these keels also extend parallel with the shell A; but they are 70 some distance in rear thereof, and overhang, as do their forward ends, and are connected to the framing G.

The rear of the chamber D is protected by a series of bars or rods, H, which extend from 75 one keel to the other, as shown in Fig. 3, the bars or rods following the contour of the keel down their inclined rear ends and along their horizontal portions to the point where the chamber D terminates. The sides of the 80 chamber D are formed by the side walls of the shell A, which are extended outward and rearward to the same distance as the keels. The side walls of the shell A, which form the side walls of the chamber D, are perforated, so as 85 to allow the free egress and ingress of water to the chamber.

The propellers E are mounted in the chamber D, and are supported in a bridge-tree or support, I, the shafts J of the propellers being 90 extended inward into the interior shell, A, so as to be connected with and operated by any suitable engine. (Not shown.)

Between and removably journaled in the keels F are a series of horizontal shafts, K, 95 which are provided with sprocket-wheels L, the latter receiving and giving motion to a number of endless pitch or toothed chains, M, as shown in Figs. 1 and 2. These chains extend up the front and the rear of the vessel, and also along the bottom, and are protected from 100 injury by the keels. At the upper ends of the

inclined chains their shafts K are each provided with a large gear-wheel, N, (shown in dotted lines in Fig. 1,) which, through an intermediate gear, O, receives motion from a 5 smaller gear, P. Motion is imparted to the gear-wheel P by means of an engine, Q, which may be of any desired construction, and the motion thus imparted to the wheel P is transmitted through the wheel O, mounted upon 10 the engine-frame, to the wheel N and to the chain.

There will, by preference, be an engine, Q, at each end of the vessel, although it will be seen that one engine could accomplish the 15 same results, but in a much less satisfactory manner.

R R indicate a series of vertical steam-cylinders, which are mounted in opposite ends of the vessels, as shown, cylinders of each set 20 being connected by a pipe or pipes, S, with a steam-chest, T, as shown in Figs. 1 and 2. These cylinders are provided with pistons, to the rods U of which are secured removable and interchangeable hammer heads or shoes 25 V, of any desired shape, the heads V being changed as the condition of the ice requires. These heads V may be sharp or blunt, and of any shape desired in cross-section.

The steam-chest T is provided with a slide- 30 valve, (not shown,) the stem or rod W of which is connected to a gear-wheel, X, by a pitman, the gear-wheel X meshing with and receiving motion from the large gear-wheel N, as shown in dotted lines in Fig. 2.

35 Steam is conveyed to the engine Q and to the steam-cylinder R from the boiler Y by means of steam-pipes Z.

The operation of the device is as follows: The engines Q in the bow of the vessel being 40 set in motion, the wheel X is caused to revolve, (through the gears P O N,) and steam is admitted to the opposite ends of the cylinder R by means of the slide-valve in steam-chest T, which is operated by the wheel X. This 45 sets the reciprocating hammers or pounders at work upon the ice, and by a succession of sharp quick blows break or crush the ice. The chains M in the meantime have also been set in motion, and as they move their teeth engage with the broken ice, pull it down under the vessel, where, by means of the horizontal chains, it is conveyed to the rear of the vessel and allowed to come to the surface and float out with the current. By providing the 55 vessel with the hammers or crushers at each end it may be used either end foremost.

The deck of the vessel is covered, so as to protect the occupants of the vessel.

Having thus described my invention, what I 60 claim is—

1. In combination with a vessel, a series of

hammers thereon for breaking the ice, an engine for imparting motion to said hammers, and an endless chain extending from the front to the rear of the vessel.

65

2. In a vessel for breaking and removing ice, the combination, with the hull or shell A, having the inclined front wall, of a series of chains mounted upon said wall and a series of hammers in advance of the latter, substantially as set forth.

3. In a vessel for breaking and removing ice, the combination, with the hull or shell A, having the inclined front wall, of the overhanging deck C, the reciprocating hammers 75 mounted in said overhanging portion, and the endless chains in rear of said hammers.

4. In a vessel for breaking and removing ice, the combination, with a hull provided with inclined end walls, endless chains extending 80 along the bottom and ends of the hull, a series of hammers at each end of the vessel, and a suitable motive power for actuating the hammers and chains simultaneously.

5. In a vessel such as described, a series of 85 ice-crushing hammers, a series of conveying-chains in rear of said hammers, and mechanism, substantially such as shown, for simultaneously operating the chains and hammers.

6. In a vessel substantially such as shown, 90 the combination, with a hull, of the keels F secured thereto, the shafts K, extending from keel to keel and provided with sprocket-wheels L, chains M, passing about the wheels, when combined with mechanism for imparting motion to the shafts.

7. In a vessel substantially such as shown, the combination, with the hull A, the deck C, overhanging the stern of the hull and forming a chamber, D, the keels F, connected to the hull 100 and extended in rear thereof up to the deck, bars H, extending from keel to keel and closing the rear and bottom of the chamber D, and a propeller, E, located within the chamber, all substantially as shown and described.

105

8. In combination with a vessel substantially such as shown and described, a hammer provided with a valve for regulating the admission of steam to its cylinder, a chain in rear of said hammer, a gear-wheel, N, secured to the 110 chain-shaft, a wheel, X, meshing with wheel N and serving to actuate the hammer-valve, a wheel, O, meshing with wheel N, a wheel, P, meshing with wheel O and serving by means of the motion imparted to it by an engine, Q, to 115 transmit motion to the gears O N, as and for the purpose set forth.
